FAUCET

Filed March 14, 1928

Lloyd G. Schimmel, INVENTOR.

BY *Arthur J. Macd*
ATTORNEY.

UNITED STATES PATENT OFFICE

LLOYD G. SCHIMMEL, OF LOS ANGELES, CALIFORNIA, ASSIGNOR, BY MESNE ASSIGNMENTS, TO HARRY R. MORRIS, OF LOS ANGELES, CALIFORNIA

FAUCET

Application filed March 14, 1928. Serial No. 261,469.

This invention relates to faucets of the general character of that shown in my application for patent filed March 9, 1927; Serial Number 173,989.

5 The main object of the present invention is to provide an improved type of faucet which is self-closing in character by water pressure, and is provided with means whereby the closing of the faucet may be cushioned so as to prevent forcible impact of the valve against its seat, and the consequent hammering or pounding of the valve when closed.

10 Still other objects may appear as the description progresses.

I have illustrated a preferred embodiment of my invention in the accompanying drawing, in which:

Fig. 1 is a perspective view of a faucet embodying my improvements, and partly in section.

Fig. 2 is a top plan view of the same with the cap removed, as seen from line 2-2 of Fig. 1.

25 Fig. 3 is a fragmentary sectional elevation of the same on line 3-3 of Fig. 2.

Fig. 4 is a fragmentary sectional elevation of the same on line 4-4 of Fig. 3, showing the valve completely open; and

30 Fig. 5 is a sectional elevation of the valve body, showing the valve approaching closing position.

Briefly described, my invention consists in a cast metal body B, having a main bore B' longitudinally formed therein and adapted to receive the valve body A carrying a valve V, and held in place by means of a cap C which operatively supports an operating member O.

40 The body B has a flanged lower end portion b adapted to abut against the top of a basin or other supporting device, and an elongated stem b' integral with the body and extended substantially therefrom. The stem b' has an inlet passage I which communicates with a chamber F' in which is held the smaller cylindrical portion a' of the member A.

45 The upper end of the body B is internally threaded to receive an extension from the

cap C, by means of which the chamber B' holding the member A is closed. The valve body A has a conical valve seat G formed therein adapted to engage a correspondingly formed portion on the valve V, and the valve stem V' is slidably held in a bore h of a boss a formed on the member A.

55 Member A has an outlet passage H which registers with a delivery passage S' of a spout S formed integral with the body. 60 Member A is stationarily held in the body B by means of a key K formed thereon, which engages a correspondingly formed key-way lengthwise of the chamber B'. It will be noted by reference to Fig. 1, that 65 when the member A is properly positioned in the faucet body, the lower end of cap C engages the upper end of the member A and provides a chamber E above the upper end of member A, and within the cap C. 70

75 The operating member O has a stem O' with an enlarged head d thereon, which operates below a threaded recess D in the upper portion of cap C. When the valve V is closed the head d is adapted to abut the upper end of the valve stem V' and when the operating member O is pressed downwardly, said head serves to urge the valve downwardly against the pressure of the water so as to permit a flow of water through the 80 valve seat, the passage H and the passage S'.

85 As indicated in Fig. 3, the cap may have the threaded portion D internally formed thereon for engagement with correspondingly formed threads on the stem O' above the head d. In such case the lead of the threads D is such that the operating member O will be rotated by the pressure of the water when the valve stem is forced against the head d.

90 I prefer to make the cap C threaded so that correspondingly formed screw threads may be formed on the stem O' as shown, or the screw threads may be omitted, in which case the member O will not necessarily turn when it is restored to normal position and 95 the valve is closed.

95 It will be observed by reference to Figs. 1, 3 and 4 that the chamber F' in the lower portion of the body is slightly larger than the portion a' of member A, so that water 100

from the inlet passage I will fill the chamber F' around the portion a'.

The walls of the chamber a' are provided with one or more peripheral ports as at f, f, for affording communication between the chamber F' and an inner chamber F within the member a' in which the valve V is seated. The positions of the ports f, f, is such that when the valve is completely open the water will flow through said ports, and thence through the valve seat and outwardly through the passages H and S', the head of the valve serving to close said ports prior to the complete closing of the valve V.

15 Thus, as shown in Fig. 5, when the ports f, f, are closed a water cushion will be provided below the valve seat and above the head of the valve, which will prevent the forcible impact of the valve against its seat and a consequent pounding which would be effected thereby.

The pressure of the water subsequent to the closing of the ports f, f, will force water through a small inlet i in a detachable end 25 closure A', which is threaded into the lower end of the cylindrical portion a'. When the chamber F is completely filled the pressure therein will be equal to the pressure in the passage I, and the valve will be gradually closed, the water serving as a cushion between the valve and its seat, gradually leaking into the passage H between the wall of said passage and a reduced extension on the valve.

35 The upper end of the member A adjacent the spout S has a shallow passage e which affords communication between the chamber E and the spout, so that at all times any water which may leak into the chamber E 40 may be drawn outwardly through the spout S due to the suction created therein when the faucet is discharging. This prevents any back pressure which may ordinarily prevent or impair the operation of the member O for opening the valve.

45 As shown in Fig. 4, when the valve is completely open the water will flow freely from passage I and chamber F', through ports f, f, valve seat G, and outwardly 50 through the passage H and the spout S. The ports f, f, are positioned so that they will be closed against the entrance of water to the passage F prior to the closing of the valve, as shown in Fig. 5, and also when 55 the valve is closed completely as shown in Fig. 1.

The operation of the faucet for discharging water from the spout thereof requires only the depression of the member O and 60 stem O', so that it will forcibly engage the stem V' and move the valve V downwardly in the chamber F against the pressure of the water, until the upper end of the head of the valve is moved below the ports f, f. 65 As long as the members O and V are held

in their depressed position, the faucet will continue to discharge water. Immediately, however, upon the release of the member O, the pressure of the water in the chamber F will serve to move the valve upwardly into the position shown in Fig. 5, whereupon the valve will gradually be restored to normal engagement with its seat G, when the water serving as a cushion above the valve is evacuated. The inner end of valve V has a reduced extension V2 which closes the valve outlet port H prior to the seating of valve V. Thus the water between the valve and its seat will gradually leak out around said extension of the valve and permit a gradual seating of the valve, thereby preventing sudden impact of the valve with its seat when the outlet is closed.

While I have shown and described but one form of my invention, it will be understood that I may change or modify the same within the scope of the appended claims without departing from the spirit thereof.

What I claim is:

1. A water faucet comprising a body having a stem with an inlet passage therein and a central chamber, an outlet from said chamber disposed at right angles to said inlet, the upper portion of said chamber being of larger area than the lower portion thereof, a valve body stationarily held in said chamber and provided with a valve chamber and valve seat, a valve slidably held in said valve chamber and adapted to control communication between said inlet and said outlet thru the seating of the valve, said valve body having a port affording communication between said outlet and said valve seat, said valve chamber having peripheral ports spaced from the valve seat open to said inlet for providing a water cushion between said seat and said ports permitting the gradual seating of said valve, and a restricted port at its end also communicating with said inlet, and means for operating said valve whereby the ports of the valve chamber may be opened and closed.

2. A water faucet comprising a body member having an inlet and an outlet and a chamber intermediate said inlet and outlet, a valve body in said chamber, an extension on said valve body, a valve enclosed by and slidably in said valve body extension, manually operable means for engaging and for opening said valve to establish communication between said inlet and outlet, said extension provided with a valve seat and a peripheral inlet adapted to be opened and closed by said valve and a restricted port below said valve, whereby water from the inlet may be admitted to said extension for automatically closing said valve, clearance being provided between the valve and seat to form a water cushion chamber when the

peripheral port is closed so as to gradually seat the valve.

3. A water faucet comprising a body having an inlet and an outlet, a valve chamber, in said body having a valve seat communicating with said outlet, said valve chamber having a peripheral port spaced from the valve seat and communicating with the inlet, and a restricted port in its end also communicating with the inlet, a valve slidable in said chamber and provided with a portion engaging the wall of said chamber, and a portion for engagement with said valve seat, said peripheral port being spaced from the valve seat and adapted to be closed prior to the seating of the valve to provide a water cushion for effecting the gradual closing of the valve subsequent to the closing of the peripheral port.

4. A water faucet comprising a body having an inlet and an outlet, a valve chamber in said body having a valve seat communicating with said outlet, said valve chamber having a peripheral port spaced from the valve seat and communicating with the inlet, and a restricted port in its end also communicating with the inlet, a valve slidable in said chamber and provided with a portion engaging the wall of said chamber, and a portion for engagement with said valve seat, said peripheral port being spaced from the valve seat and adapted to be closed prior to the seating of the valve to provide a water cushion for effecting the gradual closing of the valve subsequent to the closing of the peripheral port, said valve having an extension adapted to engage the wall of the outlet prior to the seating of the valve proper, whereby the water confined in the space between the valve and the valve seat may be gradually exhausted until the valve is finally closed.

5. A water faucet comprising a body member having an inlet and an outlet, a stationary valve body mounted in said body member intermediate said inlet and outlet, a valve chamber formed in said valve body having an outlet port communicating with the outlet of said body member, a valve seat communicating with said port, a peripheral port spaced from the valve seat and communicating with said inlet, and a restricted port in the end also communicating with said inlet, a valve slidable in said chamber and provided with a portion engaging the wall of said chamber, and a portion for engagement with said valve seat, said peripheral port being spaced from the valve seat and adapted to be closed prior to the seating of the valve to provide a water cushion for effecting the gradual closing of the valve subsequent to the closing of the peripheral port.

6. A water faucet comprising a body member having an inlet and an outlet, a

stationary valve body mounted in said body member intermediate said inlet and outlet, a valve chamber formed in said valve body having an outlet port communicating with the outlet of said body member, a valve seat communicating with said port, a peripheral port spaced from the valve seat and communicating with said inlet, and a restricted port in the end also communicating with said inlet, a valve slidable in said chamber and provided with a portion engaging the wall of said chamber, and a portion for engagement with said valve seat, said peripheral port being spaced from the valve seat and adapted to be closed prior to the seating of the valve to provide a water cushion for effecting the gradual closing of the valve subsequent to the closing of the peripheral port, said valve having an extension adapted to engage the wall of the outlet prior to the seating of the valve proper, whereby the water confined in the space between the valve and the valve seat may be gradually exhausted until the valve is finally closed.

7. A water faucet comprising a body member having an inlet and an outlet, a body therein having a valve chamber communicating with said outlet, a valve seat formed in said chamber adjacent the point of communication with said outlet, a valve slidable in said chamber, ports in said chamber communicating at different points with said inlet and closed against communication with each other by said valve, one of said ports being arranged to permit the application of pressure to the valve from the inlet for closing the other port and the valve seat and for holding the valve normally closed, said other port arranged to afford direct communication thru the valve seat between the inlet and outlet, means for opening the valve against the pressure, the valve being arranged to close said other port prior to the seating of the valve whereby a water cushion is formed in said chamber intermediate the valve and the valve seat to permit the gradual closing of the valve by pressure from the inlet applied thru said first mentioned port.

8. A faucet comprising a body member having an inlet and an outlet, a body therein having a cylindrical valve chamber, a valve slidable in said chamber, means for opening the valve against the pressure from said inlet, an outlet port in said chamber communicating with said outlet, and a valve seat adjacent said port, a peripheral port in said chamber communicating with said inlet, an auxiliary port in the end of said chamber also communicating with the inlet, said valve having a peripheral portion for opening and closing the peripheral inlet port of the chamber, an intermediate portion for opening and closing said valve seat, and a reduced portion for opening and clos-

ing said outlet port, whereby direct communication may be established between the inlet and the outlet thru said peripheral inlet port when the valve is open, and a water cushion is formed between the valve and the valve seat when said peripheral inlet port is closed to permit the gradual seating of the valve while the reduced portion of the valve is engaged with the wall surrounding the outlet port.
